UNITED STATES PATENT OFFICE.

SAMUEL J. MOLNER, OF CHICAGO, ILLINOIS, ASSIGNOR TO ILLINOIS MOULDING COMPANY, OF CHICAGO, ILLINOIS, A CORPORATION OF ILLINOIS.

DESIGN FOR A MIRROR FRAME.

Application filed February 9, 1925. Serial No. 12,325. Term of patent 3½ years.

To all whom it may concern:

Be it known that I, SAMUEL J. MOLNER, a citizen of the United States, residing at Chicago, in the county of Cook and State of Illinois, have invented a new, original, and ornamental Design for Mirror Frames, of which the following is a specification, reference being had to the accompanying drawing, forming part thereof.

The figure is a front elevational view of a mirror frame, showing my new design.

I claim:

The ornamental design for a mirror frame, as shown.

SAMUEL J. MOLNER.
